UNITED STATES PATENT OFFICE.

HUBBARD F. HURD, OF TROY, NEW YORK, ASSIGNEE TO CLUETT, PEABODY & CO., INC.,
OF TROY, NEW YORK, A CORPORATION OF NEW YORK.

FOLD-COLLAR.

1,267,770.

Specification of Letters Patent. Patented May 28, 1918.

Application filed July 19, 1915. Serial No. 40,557.

To all whom it may concern:

Be it known that I, HUBBARD F. HURD, a citizen of the United States, residing at Troy, county of Rensselaer, and State of New York, have invented certain new and useful Improvements in Fold-Collars, of which the following is a specification.

Reference may be had to the accompanying drawings, and the reference characters 10 marked thereon, which form a part of this specification. Similar characters refer to similar parts in the several figures therein.

This invention relates to a type of fold-collar in which the ends of the folded-over 15 top retreat obliquely from the neighboring edge of the band forming a more or less flaring opening between the ends of the top when the ends of the collar are fastened together as in use.

20 In the manufacture of such fold-collars, it has been customary to extend the end-edges of the corners of the tops, where inserted between the plies of the band, in the same general direction or line as the edges of the exposed end-portions of the top adjacent to the edge of the band.

25 The inserted corner portions of the top are thus located between the band-plies at a point where the band is exposed to view 30 in use through the opening between the divergent ends of the top, making the edge of the projecting end-portions of the band unduly thick and stiff, and forming an unsightly variation in the surface of the band 35 along the outline of the inserted corner of the top.

The principal object of the present invention is to provide a better fitting collar of the type referred to, as well as to improve 40 the appearance of the collar.

Figure 1 of the drawings is a front view of a fold-collar embodying my invention.

Fig. 2 is a plan view of an end-portion 45 of the collar with the top opened out flat and the uppermost band-ply broken away to expose the inserted corner-portion of the top.

Referring to the drawings wherein the invention is shown in preferred form, 1 is the band of the collar, and 2 is the top having an edge-portion, 3, inserted between the band-plies in the usual manner.

The exposed end-portions of the top re-

treat obliquely or divergently from the neighboring edge of the band as at 4, forming a more or less flaring opening as shown 55 in Fig. 1.

In carrying out my invention I make each end of the top adjacent to the band in the form of an angle as shown at 5, which angle is bisected by the neighboring edge, 6, of 60 the band, causing the end-edge, 7, of the inserted corner of the top to retreat obliquely inwardly between the band-plies to substantially the same, or a slightly greater, 65 degree than the edge, 4, of the exposed end-portion of the top retreats obliquely inwardly from the neighboring edge of the band.

I use the term "inwardly" with reference 70 to the neighboring end of the collar.

By forming the inserted corner of the top with the obliquely retreating end-edge, 7, as described, when the top is folded upon the band, the portion of the band within which said inserted corner is located, is covered and concealed from view by the folded-over top, and the longer portion of the band lying outwardly beyond the point of junction of the exposed end of the top with the neighboring edge of the band is not reinforced or thickened by the inserted corner-portion of the top.

The edge-portions of the band immediately adjacent on the outer side to the end-portions of the top are thus left of normal 85 thickness and permit the meeting corners of the folded-over top to be drawn into close-fitting relationship, which adds to the attractive appearance of the collar, an effect 90 which cannot be obtained when such edge-portions of the band are unduly thickened.

What I claim as new and desire to secure 95 by Letters Patent is—

A launderable fold-collar comprising a band and a folded-over top inserted in the 95 band, the exposed end-portions of the top retreating obliquely inwardly from the neighboring edge of the band and its inserted end-portions similarly retreating obliquely inward between the band-plies. 100

In testimony whereof, I have hereunto set my hand this 12th day of July, 1915.

HUBBARD F. HURD.
